Attest

UNITED STATES PATENT OFFICE.

WILLIAM GOODROW, OF CHICAGO, ILLINOIS.

WINDOW CORNICE AND THE LIKE.

Application filed July 10, 1925. Serial No. 42,716.

To all whom it may concern:

Be it known that I, WILLIAM GOODROW, a citizen of the United States, residing at Chicago, in the county of Cook and State 5 of Illinois, have invented certain new and useful Improvements in Window Cornices and the like, of which the following is a specification.

This invention has to do with improvements in the construction of window cornices and similar structures. In order that the features of the invention may be better understood and their significance and usefulness more fully appreciated, I will first 10 explain certain facts in reference to the manufacture and sale of articles of this general class. Articles such as the foregoing generally have to be specially constructed to meet certain exact specifications of size, 15 shape, etc., and it is furthermore necessary, in this connection, to make provision for allowing the purchaser a very wide selection of designs and materials. For example, a window cornice of a certain size and shape may 20 be made from trimmings and moldings of a large number of different designs. It is not practicable to carry all conceivable sizes and shapes in stock, and much less is it possible to carry each size and shape in 25 stock of a large number of different designs and combinations of designs. As a result, 30 commercially it is only feasible to handle materials of this kind in the raw condition, and practically it becomes necessary to 35 make provision for individually assembling each particular order according to its individual specifications or requirements.

Practically also a very large percentage 40 of the orders for this class of material are placed with retail merchants, such as department stores, the customer selecting the particular design which he wishes used for the running strips of the molding or like article which he wishes to order. It then 45 becomes necessary to assemble or "manufacture" the completed article according to such selections.

According to present processes and arrangements of molding, etc., the foregoing 50 condition has heretofore made it necessary

for the store or selling agent to then proceed and cut the different parts to proper size and thereafter assemble them by gluing, nailing, and similar operations. This has entailed an enormous amount of overhead 55 expense and clerical work as well as actual labor of fabrication, so that the sale of articles of this class has not received the same impetus or consideration which would otherwise be possible. Furthermore, when the 60 completed article is thus assembled and delivered to the purchaser at the store it becomes necessary for him to carry away a bulky and unwieldy package; or else it becomes necessary for the store to ship out a 65 large package which must in every instance be carefully packed to avoid damage.

In other cases where articles such as window cornices and the like have been completely fabricated at the factory according 70 to definite specifications, the delivery cost has been greatly increased by reason of the necessity of careful boxing and packing of a bulky, unwieldy article, and in this connection it is frequently found impossible to 75 "nest" articles of this kind, so that the bulk and cost of the shipment are accordingly increased. Furthermore, fabricated articles of this sort take a very high 80 freight rate, and this further adds very 85 largely to the delivery cost.

The main object of the present invention is to provide molding strips and corner or junction pieces for use therewith, which parts are so formed and arranged that 90 they can be very easily cut by simple operations to the necessary sizes for assembly into the complete article such as a window cornice, or the like; and furthermore to so arrange and construct these parts that no matter what length or size the running strips 95 are cut, they will also present the proper holes to receive the dowel pins for connection to corner or junction pieces or other running strips, and without the necessity of any drilling operations on the part of the person assembling the job.

It is a further object in connection with the foregoing to provide the running strips 100 themselves with continuous perforations

which are uniformly spaced throughout the length of the running strips, so that no matter where said strips are sawed or cut off, these perforations will be exposed in the proper positioning and relative placing with respect to each other and with respect to the surfaces of the strip to receive the dowel pins for connection either to other strips or to corner or junction pieces.

10 It is a further object of the invention to establish the foregoing continuous perforations by forming the molding strip itself from two companion sections which have oppositely placed semi-circular complementary channels, so that when said companion sections are set together, said channels will cooperate to establish the completely circular perforation or hole of uniform size.

15 20 Preferably the foregoing result is secured by forming the molding strip from a pair of companion strips set together in flat fashion and held by gluing or otherwise; in which case it is also desirable to use a tongue and groove arrangement in the companion faces of the two strips so as to insure that they will be placed on exact registry when assembled. Another way to establish the desired construction is by providing one or 25 30 more grooves in the main strip of molding, each groove having a semi-circular channel in its floor, together with a relatively small generally rectangular strip set into and closing up said groove, but provided on its interior face with a companion semi-circular channel.

35 40 Ordinarily, the dowel pins will be permanently built into the corner or junction blocks and set at the proper spacing to seat snugly into the perforations of the running strips when the parts are assembled, but in some instances the dowel pins may be left loose, so that the assembler may himself set them into the corner or junction blocks as 45 well as the running strips.

45 Referring to the drawing:

50 Figure 1 shows an elevational view of the upper portion of a window casing having applied thereto a window cornice embodying the features of the present invention, and showing also the curtains and drapes depending from said cornice.

55 Fig. 2 shows a horizontal section on the line 2—2 of Fig. 1, looking in the direction of the arrows;

60 Fig. 3 shows a perspective view of a corner block together with a short section of running strip embodying the features of the present invention and slightly separated in position from the corner block;

65 Fig. 4 shows a vertical cross section on the lines 4—4 of Figs. 1 and 2 looking in the direction of the arrows, but on enlarged scale;

65 Fig. 5 shows a cross section through the

modified form of molding or running strips; and

70 Fig. 6 shows a cross section through another modified form of molding or running strip.

75 Referring first to Figs. 1 and 2, I have therein chosen to illustrate the features of the invention as applied in the case of a window cornice, but it will be understood that the features of the invention may also 80 be applied to many other articles as already explained.

85 The window cornice illustrated in the drawing includes a running strip of molding 7 having its exposed face suitably ornamented and of whatever design may be selected. This running strip is generally used in conjunction with corner blocks or junction blocks 8 and 9 at its ends, and these 90 likewise may be of any selected design and ornamentation. Usually also there are side strips 10 and 11 reaching from the corner blocks 8 and 9 to the wall 12 or the upper portion of the window casing or other structure to which the window cornice is attached. In the particular construction illustrated, the attachment is effected by means of a pair of screw hooks 13 and 14 reaching out from the wall or structure 12 and engaging companion eyes 15 and 16 on the end sections 10 and 11, respectively. 95 This, however, is a matter of detail and individual selection.

100 The running strip 7, and also the end strips 10 and 11 are each provided with a pair of longitudinally extending holes or 105 passages 17 and 18. These are parallel to each other and reach the full length of the molding strip, preferably being continuous throughout said length. Preferably also 110 these holes 17 and 18 are equi-distantly spaced from the upper and lower edges of the strip 7 or the strips 10 and 11, and also the passages in the strips 10 and 11 are 115 preferably spaced at equal and similar spacing 110 with respect to the passages in the strip 7. In other words, where the design of the sections 10 and 11 are the same as the design of the section 7, all of these parts may be 115 cut from a single continuous strip of molding by square sawing operations; whereas, if the designs of the different sections are 120 different from each other they will naturally be cut from different strips, but owing to the uniformity of manufacture, the perforations in all of them will be equi-distantly and similarly placed.

125 The corner or junction blocks 8 and 9 are provided with outstanding dowel pins 19, said pins reaching straight out from the surfaces of the corner blocks, and being placed at the same spacing as the spacing of the perforations 17 and 18. Consequently, the corner blocks and molding strips 130 may be set together and secured by the dowel

pins no matter at what point the molding strip may be cut within its length, so that the artisan has assurance that no matter where he cuts straight across the molding 5 strip he will expose perforations which are correctly spaced and placed to receive the dowel pins of the companion blocks. To the same extent also all of the parts are fully interchangeable.

10 The perforations 17 and 18 may be formed in any convenient manner, but the arrangements illustrated in Figs. 4, 5 and 6 are favored. In the construction of Fig. 4 the strip 7 comprises a pair of companion strips 15 20 and 21 which have in their opposing faces semi-circular channels which, when the companion strips are set together, serve to establish the complete circular perforations 17 and 18. This is so evident from Fig. 4 as 20 not to require consideration. However, in order to ensure proper registration of the strips 20 and 21, I prefer to provide a tongue and groove connection 22 on their companion faces, as clearly indicated in 25 Fig. 4.

In the modified construction of Fig. 5, I have illustrated the rectangular grooves 23 and 24 formed in the upper and lower edges respectively of the strip 7, together with 30 other strips 25 and 26 which may be set into and occupy the major portion of the said grooves. These grooves and strips are also provided with companion semi-circular channels on their faces, so that when set 35 together they also establish the complete circular perforations.

The construction of Fig. 6 is similar to that of Fig. 5, with the exception that the grooves 27 and 28 are in the present instance 40 formed in the back faces of the molding strip 7, the strips 29 and 30 being set into said grooves from said back face.

It will be evident that the construction shown in Figs. 5 and 6 are such as to make 45 it unnecessary to make any special provision for ensuring proper registration of the companion semi-circular channels. It will also be apparent that each of the different constructions illustrated is such as to make it 50 possible to establish the continuous perforations in strips of any selected length or design and by manufacturing processes which are extremely simple and can be cheaply and accurately perforated.

55 It will also be understood that although I have illustrated the features of the invention as having particular application to a window cornice construction, I do not intend to limit the said features thereto, except as I may do so in the claims.

I claim:

1. As a new article of manufacture, an ornated frame comprising running strips together with corner or junction 65 blocks located between the adjoining ends

of said running strips and establishing connection between them, the exposed faces of all of said parts being suitably ornamented, each running strip comprising a pair of companion sections set together and secured 70 in suitable fashion, said companion sections having companion semi-circular channels establishing circular perforations or holes extending throughout the entire length of the strip, the holes in each strip being parallel to each other throughout their length, and the holes in all of the strips being equally spaced with respect to each other, the ends of the strips being cut at right angles to the holes aforesaid and the corner 75 or junction blocks being seated squarely against said ends, together with dowel pins on the abutting faces of the different corner and junction blocks reaching outwardly therefrom at right angles, and spaced at the same spacing as the perforations of the strips aforesaid, substantially as described.

2. As a new article of manufacture, an ornated frame comprising running strips together with corner or junction 80 blocks located between the adjoining ends of said running strips and establishing connection between them, the exposed faces of all of said parts being suitably ornamented, each running strip comprising companion 85 sections set together and suitably secured, said sections having semi-circular longitudinally extending channels on their abutting faces serving to establish continuous circular holes throughout the length of the running strip, said holes being equi-distantly spaced 90 throughout their length, the end portions of the running strips being cut at right angles to the holes, the holes of the different strips being equally spaced, dowel pins on the 95 abutting faces of the corner or junction blocks and extending at right angles therefrom, said dowel pins being placed at the same spacing as the holes aforesaid, whereby the dowel pins of the corner or junction 100 blocks may be used interchangeably in the 105 perforations of different running strips, substantially as described.

3. As a new article of manufacture, an ornated frame including a running strip 110 together with corner or junction blocks, both parts having their exposed faces suitably ornamented, the running strip comprising companion strips having semi-circular parallel channels on their companion 115 faces serving to establish continuous circular holes or perforations equi-distantly spaced throughout their length, and each corner or junction block having a pair or dowel pins projecting at right angles from 120 its abutting face and equi-distantly spaced with respect to the perforations aforesaid, substantially as described.

4. As a new article of manufacture, a frame including a running strip and a 130

corner or junction block, said running strip having a pair of continuous perforations extending throughout its length and equi-distantly spaced at all points, and the corner or junction block having a pair of dowel pins projecting at right angles from its abutting surface and spaced equi-distantly with respect to the perforations of the running

strip, whereby the running strip may at any point be cut at right angles to the perforations at such point and the dowel pins of the corner or junction block set into the ends of the perforations thus exposed, substantially as described. ¹⁰

WILLIAM GOODROW.
